AXEL RUGARD, OF LA CONNER, WASHINGTON

FLUE CLEANER

Application filed July 25, 1930. Serial No. 470,845.

This invention is directed to flue cleaners or sweepers wherein provision is made for the manual reciprocation of the cleaner longitudinally of the flue, with the cleaning elements held in cleaning contact with the walls of the flue under the influence of a weight.

The primary object of the present invention is the provision of a flue cleaner of this type wherein the cleaning elements involve two sets of brushes mounted on and connected to relatively movable frames, one of the frames being supported, as by a cable or the like, for the operation of the cleaner and the other of the frames being connected to a weight, the relative separation of the frames compelling a spreading movement of the respective sets of cleaners to engage the sides of the flue and scrape therefrom any accumulated soot or dirt.

20 The invention is illustrated in the accompanying drawing, wherein:—

Figure 1 is a side elevation of the improved flue cleaner constructed in accordance with the present invention.

25 Figure 2 is a similar view taken at right angles to Figure 1.

Figure 3 is a section on the line 3—3 of Figure 1.

30 Figure 4 is an enlarged perspective view of one of the removable cleaners.

The improved cleaner comprises a main frame made up of relatively reversed rod loops 1, each including spaced parallel side bars 2 having a rounded terminal 3. The rod loops are arranged in relatively reversed order so that the rod loop of one, hereinafter termed the upper rod loop, is at the uppermost end of the frame, while the rod loop of the other, hereinafter termed the lower rod loop, is at the lowermost end of the frame. A plate 4 is secured to the free terminals of the bars 2 of the upper rod loop, this plate being thus arranged adjacent the lower end of the frame. A similar plate 5 is secured to the free terminals of the bars 2 of the lower rod loop, this plate being thus arranged near the upper end of the frame.

The plates 4 and 5 may, if desired, be of the shape illustrated more particularly in Figure 3, constituting in effect diametrically opposed

pairs of arms 7. The plates are fixed to the respective rod loops in one diametric pair of arms and the other diametric pair of arms of the plate are formed with openings 8 through which the bars of the other rod loop are freely 55 slidable. Thus the plate 4 is fixed at the lower end of the upper rod loop and slidably receives the bars of the lower rod loop, while the plate 5 is fixed to the bars of the lower rod loop and slidably receives the bars of the upper 60 rod loop.

Intermediate the bars 4 and 5 is arranged another plate 9, hereinafter termed the operating plate, this plate being, if desired, of the same form as the plates 4 and 5 in plan 65 with the respective arms formed with openings to permit free sliding movement of the bars 2 of both rod loops. Pivotedly connected to certain of the arms of the upper plate 5 are cleaning arms 10, these arms extending to 70 a point below the operating plate 9 and terminally provided with cleaning brushes, to be later described.

Links 11 of the particular shape shown are terminally connected to the operating 75 plate and to the arms 10 intermediate their ends. Similar arms 12 are pivotally supported on the operating plate and connected by links 13 corresponding to links 11 to the plate 4, secured at the lower end of the upper 80 rod loop.

The cleaning brushes are shown more particularly in Figure 4, each comprising upper and lower strips 14 and 15 of right angle form in plan and secured together by a 85 plate 16 having a portion 17 underlying the lowermost strip, the rear portion of the plate being bent at right angles to the portion 17 and its upper portion 18 bent backwardly or rearwardly onto the upper strip 14, the 90 clamping action thus secured holding the strips 14 and 15 in position to receive and grip brushing or cleaning elements 19, preferably wire brushes, arranged between the strips and projecting therebeyond. That 95 portion of the plate 16 at the apex of the strips 14 and 15 is formed with an opening 20 to fit over the lower end of one of the arms 10 or 12, the arm being suitably reduced for this connection, and a nut or other fastening 100

means, such as a wing nut 21, holds the cleaner in fixed relation to the particular arm. It is understood that each of the arms are provided with a cleaner of this right angle form so that considered collectively the arms carry a series of cleaners which provide a cleaning area corresponding to the shape and at least coincident with the periphery of the flue to be cleaned.

10 A cable or other supporting means, as 22, is secured to the terminal 3 of the upper rod loop, a weight 23 being correspondingly secured to the terminal 3 of the lower rod loop. As the cleaner is lowered into the flue, indicated at 24, the weight 23 acts to move the plates 4 and 5 toward each other, the lower rod loop moving under the influence of the weight and the upper rod loop being prevented from free downward movement by the operator in his grip on the cable 22. In this relative movement, the arms 10 and 12 are swung outwardly incident to the provision of the links 11 and 13 in an obvious manner. Thus the cleaning brushes are brought into contact with the surface of the flue 24 and as the cleaner is reciprocated longitudinally of the flue the cleaning brushes remain in contact with the flue under the influence of the weight 23 and thus the soot and other refuse is readily scraped from the flue and falls into the bottom of the latter, to be removed in any convenient manner.

I claim:—

1. A flue cleaner including rod loops comprising parallel rod sections and loop sections, said rod loops being arranged in opposed relation with the rod sections parallel and equi-distant from each other, an upper plate slidably receiving one of the rod loops and secured to the other and adapted to hold said rod loops in relative positions, a lower plate secured to the rod loop slidably received by the upper plate and slidably receiving the rod loop secured to said upper plate, an intermediate plate having openings through which the parallel rod sections freely pass, separate brush-carrying means pivoted to the upper plate and the intermediate plates, and links connecting the brush-carrying means and the intermediate and the lowermost plates.

2. A flue cleaner, comprising a rod looped at its lower end to provide vertical legs, an upper plate secured to the free ends of said legs, said plate having oppositely disposed openings intermediate the legs, a second rod looped at its upper end to provide vertical legs, a lower plate secured to the free ends of the legs of said second mentioned rod, said lower plate having oppositely disposed openings intermediate the legs of said second mentioned rod, the legs of the first mentioned rod passing freely through the intermediate openings in the upper plate and the legs of the second mentioned rod passing

freely through the intermediate openings in the lower plate, an intermediate plate having openings through which all the legs freely pass, brush-carrying arms pivoted to the upper plate, links connecting said brush-carrying arms with the intermediate plate, brush-carrying arms pivoted to the intermediate plate, and links connecting the last mentioned brush-carrying arms with the lower plate.

In testimony whereof I affix my signature.

AXEL RUGARD.
